BARTON A. BALLOU AND FREDERICK A. BALLOU, COPARTNERS AS B. A.
BALLOU & COMPANY, OF PROVIDENCE, RHODE ISLAND.

HINGE-JOINT FOR BREASTPIN PIN-TONGUES.

SPECIFICATION forming part of Letters Patent No. 729,383, dated May 26, 1903.

Application filed October 4, 1902. Serial No. 125,918. (No model.)

To all whom it may concern:

Be it known that I, EUGENE W. MOREHOUSE, a citizen of the United States, residing at Providence, in the county of Providence and State of Rhode Island, have invented 5 certain new and useful Improvements in Hinge-Joints for Breastpin Pin-Tongues, of which the following is a specification, reference being had therein to the accompanying drawings.

Like letters indicate like parts.

Figure 1 is a perspective view of the blank (cut from sheet stock) of the hinge-joint of my improved pin. Fig. 2 is a top plan view 15 of the same after it has been cupped and formed by a suitable die and plungers. Fig. 3 is an edge view of the same. Fig. 4 shows the form of said hinge-joint after it has been bent into a V shape. Fig. 5 shows in side 20 elevation a back-plate of a breastpin having the bent-up hinge-joint soldered thereon. Fig. 6 is a perspective view of the square-headed pin used as a pin-tongue for said breastpin. Fig. 7 is a side elevation of the said 25 back-plate and hinge-joint soldered thereon, the pin-tongue mounted in the hinge-joint, together with the pin-catch to engage the free end of the pin-tongue. Fig. 8 is a sectional view, as seen on line xx of Fig. 7. Figs. 9, 10, 30 11, 12, and 13 are views of a modified form of my invention, of which Fig. 9 is an inverted plan view. Fig. 10 is a front elevation of said modified form of the hinge-joint after it is bent into a V shape. Fig. 11 is a view 35 partly in elevation and partly in longitudinal section, as seen on the lower line of the pin-tongue C', shown in Fig. 9. Fig. 12 is a plan view of the butt-end of the pin-tongue with a portion thereof cupped up to form the 40 pivotal bearing of the pin-tongue, and Fig. 13 is a sectional view, as seen on line yy of Fig. 11.

My invention relates to the combination of hinge-joints and pin-tongues in breastpins 45 and similar articles of personal wear; and it consists of the novel and useful construction and combination of the several parts herein-after described, as specifically set forth in the claims.

In the drawings, A represents an oval blank

cut from sheet metal. This blank is subjected to die action, by which it is formed as shown in Figs. 2 and 3, where it is seen there are two circular recesses or sockets a and b in the line of the major axis of the blank A, 55 near the ends thereof, and two annular depressions c and d , ninety degrees in extent, opening out from the sockets or recesses a and b , as fully shown in Figs. 2 and 3. The blank after it has been formed as shown in Figs. 2 and 3 is centrally bent transversely 60 into a general V shape, as illustrated in Fig. 4. It is then soldered at its base e to the back-plate B of the breastpin or similar article of personal wear and forms the hinge-joint. 65

The pin C is resilient, being made of tempered wire, and has a squared head f , Fig. 6, and the headed end is laid in the V-shaped opening of the bent-up hinge-joint, Fig. 4. This bent-up hinge-joint (with the pin-head 70 in it) is pinched together by pliers, and the head f then lies in the two circular sockets a and b , as shown in Figs. 7 and 8. A catch D is soldered to the plate B and receives the outer end of the pin C. 75

As seen in Fig. 8, the hinge-joint when bent up has its opposite sides substantially parallel. The two depressions c and d when the ends of the hinge-joint are bent and pressed, as seen in Fig. 8, constitute an open slot of a 80 width slightly exceeding the diameter of the pin C. The pin-head f practically serves as a fulcrum or pivot, and as it fits in the circular sockets a and b , as plainly shown in Fig. 7, the pin-tongue C is freely movable from the positions shown in dotted lines in said figure to the position shown therein in solid lines, but, as is evident by an examination of Fig. 8, is prevented from axial rotation by its straight sides being in constant contact with the straight bottoms of the sockets a and b . The shoulders formed in the hinge-joint by those edges of the depressions c and d which extend at right angles from the plate B serve as a stop to 85 limit the movement of the pin-tongue C in swinging outwardly, and the other shoulders formed by those edges of the said depressions which extend parallel with the plate B serve as a fulcrum on which to spring or bend the resilient pin-tongue C when bending the same 90 95 100

to a position to enter and engage with the pin-catch D.

- In Figs. 9 to 13, inclusive, is shown a modified form of my invention in which the blank 5 A' is made with only one socket a', as seen in Figs. 10 and 13, and bent, as shown in Fig. 10, and soldered to the plate B', as shown in Figs. 9, 11, and 13. The pin C' has an integral head f', whose edge f'' is in line with the 10 surface of the pin C, and whose edge f''' is at a right angle thereto, and whose outer edge is curved, as shown in Fig. 11. By die action the side of the pin-head f' is cupped and a square-ended circular projection is thrown 15 out on one side of the pin-head, as seen at m. This pin-head, with its projection m, is placed in the V-shaped opening of the hinge-joint A', Fig. 10, and said hinge-joint is pressed or pinched together by pliers to the form shown 20 in Fig. 13 (which figure is a sectional view, as seen on line y y of Fig. 11.) As plainly shown in Fig. 13, the projection m of the pin-head f' then fits in the socket a' of the hinge-joint A' and permits the movement of the pin 25 c' in the plane of the axial line of the plate B'. The square corner at the end of the edge f''' of the pin-head f' furnishes a fulcrum for the springing of the resilient pin C' to a position to enter and engage the catch D.
- 30 By this invention I dispense with a separate pivot to connect the pin-tongue with the hinge-joint and save the labor of fitting such pivot to one member of the hinge and mounting it loosely in the other, which has hitherto been necessary in constructing such hinge

connections. My said method of manufacture is cheaper than that usually adopted and is equally efficient.

I claim as a novel and useful invention and desire to secure by Letters Patent— 40

1. The combination of a pin-tongue having a substantially cubical head whose dimensions exceed the diameter of said pin-tongue, and a pliable hinge-joint having two sockets and two quarter-circular annular depressions 45 opening into said sockets, respectively, which hinge-joint is adapted, when bent, to receive rotatably said pin-head in said sockets and to receive the part of said pin-tongue nearest said pin-head in the slot formed by said two 50 depressions when the hinge-joint has been bent so as to allow a limited oscillation of said pin-tongue therein, upon said pin-head as a pivot, substantially as shown.

2. As a new article of manufacture, a jeweler's finding for the hinge-joint of a breast-pin or similar article of personal wear, consisting of an oblong blank having on its major diameter two circular sockets near the end thereof and annular depressions, a quarter-circle in extent, on the edge of said blank adjacent to and opening into said sockets, respectively, substantially as described. 55

In testimony whereof I affix my signature in presence of two witnesses.

EUGENE W. MOREHOUSE.
